(57) **CLAIM**

The ornamental design for a bird feeder, as shown and described.

DESCRIPTION

FIG. 1 is a top, front, right perspective view of a bird feeder shown in a condition of use;

FIG. 2 is a top, front, right perspective view of the bird feeder of FIG. 1;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a bottom, front, right perspective view thereof.

The broken lines in the drawings depict environmental structure and form no part of the claimed design.
